NORTON A. MEARS AND DIBRELL P. HYNES, OF CHICAGO, ILLINOIS, ASSIGNEES TO
CHICAGO FORGING & MANUFACTURING CO., OF CHICAGO, ILLINOIS, A CORPORATION
OF ILLINOIS

HOOD LATCH

Application filed May 10, 1929. Serial No. 361,932.

Our invention relates to locking or latching means for closures and is herein shown as applied to an automobile hood. One purpose is the provision of simple and easily operated means for securing an automobile hood in closed position. Another object is the provision of means for drawing the hood downwardly and inwardly against its abutment on the frame of the automobile. Another object is the provision of means for permitting the actuation of a plurality of hood latching means by a single handle adapted both to latch and unlatch the hood and to raise and lower the hood. Other objects will appear from time to time in the course of the specification and claims.

The invention is illustrated more or less diagrammatically in the accompanying drawings, wherein—

Figure 1 is a side elevation;

Figure 2 is an interior elevation;

Figure 3 is a section on the line 3—3 of Figure 2;

Figure 4 is a section on the line 4—4 of Figure 2;

Figure 5 is a section on the line 5—5 of Figure 2;

Figure 6 is a view similar to Figure 2 illustrating the device in unlocked position;

Figure 7 is a partial vertical section of a modification;

Figure 8 is a view similar to Figure 7 of a further slight modification; and

Figure 9 is an interior elevation of a variant form.

Like parts are indicated by like symbols throughout the specification and drawings.

Referring first to Figures 1 and following, A generally indicates the body of the vehicle and A¹ a hinged hood member. A² indicates the vehicle frame, and A³ a hood abutment secured thereto. A⁴ A⁴ indicate terminal abutments for the ends of the hood. Mounted within the hood is a rock shaft generally indicated as B having the terminal offset portions or cranks B¹ B¹ adapted to engage locking abutments B² B², herein shown as mounted on the members A⁴, having the faces B³ inclined upwardly and inwardly from the hood. B¹² indicates a projection at the up-

per end of each such face. The rock shaft may be mounted as on a plurality of terminal bearing members B⁴ and a plurality of adjacent central bearing members B⁵. Between the central members the rock shaft is indicated as offset or deformed at as B⁶, this offset portion including what may be called a cam portion B⁷ which may be more or less curved as shown for example in Figure 4.

C indicates a shaft with the exterior handle C¹, the shaft passing through the hood. At its inner end is mounted the cam member generally indicated as C² which may have the hook or horn C³ adapted to cooperate with the portion B⁷ of the offset B⁶. It is further provided with an apron B⁸ which, when the device is in locking position, as shown in Figure 2, overlies the offset portion and constrains it to the full line position of Figure 4. The flange B⁹ of the apron B⁸ engages the side B⁷ of the offset and limits further counter-clockwise movement, taking the parts in the position in which they are shown in Figure 2. This limit is preferably so arranged that at that position the handle C¹ is horizontal, for convenience. It will be understood that when the parts are in the full line position in which they are shown in Figure 2 the offsets or crank arms B¹ are thrust into locking engagement with the inclined edges B³ of the abutments B² and the result is the drawing downwardly and inwardly of the lower edge of the hood. B¹⁰ indicates a depression in the apron B⁸, adapted to hold the parts locked, when it engages the portion B⁷.

Taking the parts for example in the position in which they are shown in Figure 2, when the device is rotated clockwise, the horn C³ engages the offset B⁷ and exerts a camming action against its lower inclined portion and thus rotates the entire rock shaft in such fashion as to withdraw the cranks B¹ from the abutments B². The cam body and apron B⁸ are so proportioned as to limit the rotation of the handle to an arc of 180 degrees, in such fashion that the handle is in horizontal position when the cranks B¹ have been removed to inoperative position and is therefore in the most convenient position for

the manual lifting of the now released hood.

D indicates an additional stop which may be mounted for example on the frame A², extending upwardly therefrom at a point within the abutment A³, as shown in Figure 4. It may have an outwardly curved or inclined portion D¹. Opposed to the member D is a stop or holding member generally indicated as D², secured to the inner face of the hood as at D³. The parts are preferably so spaced that when the hood is lowered into the position in which it is shown in Figure 4 the member D² slides over the inclined portion D¹, which serves to guide it, and abuts against the member D, thus holding the lower edge of the hood from outward movement.

It may be desirable to employ yielding means to prevent rattling of the parts and also to compensate for irregularities in assembly of the parts. Thus in Figure 7 we illustrate a spring E which may be compressed between the inner face of the hood and the cam member generally indicated as C², slidably mounted upon the square portion C¹⁰ of the shaft C.

In the variant form of Figure 8 the cam member C² may be mounted slidably on the reduced square portion E² of the shaft on which the handle C¹ is mounted. The reduced portion is shown as provided with a head E³ and a spring E⁴ is compressed between the head E³ and the cam member C². The spring E⁴ may also aid in the locking effect of the engagement of the depression B¹⁰ and the member B⁷. E¹ is a spacing sleeve which may also serve for mounting the shaft C to the hood member A¹. Such yielding means are to be taken as examples of preventing excessive strain of the rock shaft B owing to irregularities of mounting of the locking abutments B². As illustrated in dotted lines in Figure 7, the cam portion B⁷ of the rock shaft tilts the cam member C² and bending and deforming of the rock shaft B is thus made unlikely.

Such yielding means are also desirable to eliminate possible rattling of parts and therefore we do not wish to be limited to specify detail except so far as we limit ourselves in the claims.

Referring to the form of Figure 9 the rock shaft G is provided with terminal recurved portions G¹ which are received in bearing members G² on the interior of the hood. It will be observed that in the form herein shown no bearings are shown between the bearings G² and the intermediate bearings G³ adjacent the central portion of the rod. It will be understood that additional bearings may be interposed if necessary. The recurved portion G¹ is connected with the body of the rod by a short stretch G⁴ which, when taken in connection with the adjacent portions of the rod G, serves as a crank arm for engaging any suitable latch abutments G⁵.

It will be realized that whereas we have described and shown a practical and operative device, nevertheless many changes might be made in the size, shape, number and disposition of parts without departing from the spirit of our invention. We therefore wish our description and drawings to be taken as in a broad sense illustrative and diagrammatic rather than as limiting us to our specific showing.

The use and operation of our invention are as follows:

In securing the hinged hood portions of automobiles and plates, securing means are desirable which hold the hood firmly in position, which draw the lower edge of the hood downwardly, to hold it tight, and which also draw it inwardly or prevent it from outward movement. We have provided means for effecting these results which are simple and efficient and which respond to the movement of a single handle member. This handle member, being preferably situated midway between the ends of the hood, not only serves to control the hood latching means, but also serves as a handle for lifting the hood when the latches are disengaged. We preferably employ a handle of somewhat elongated form, to serve conveniently as a lifting as well as a turning means. We preferably so proportion the parts that the handle C¹ is in generally horizontal position when the latch members B¹ are disengaged. We find it convenient to limit the rotation of the handle to an arc of 180 degrees, whereby the handle is also in horizontal position when the hood is latched.

In order to provide simple means for latching the hood in position we employ a rock shaft the ends of which may be bent or deformed to form crank arms or the equivalent of crank arms. In other words some part of the rock shaft, preferably the ends in so far offset from the center of rotation of the body of the rock shaft, that rotation of the rock shaft imparts such movement to the end or ends as will cooperate with a latch abutment to have the desired locking effect.

Referring for example to Figure 4 or 5, we employ latch abutments B², which may be mounted on the members A⁴ and which are provided with surfaces or edges B³ upwardly and inwardly inclined. In response to a locking rotation of the handle C¹ the crank ends of the rock shaft are given what in Figures 4 and 5 would be a clockwise rotation. They engage the inclined surfaces B³ and the result is a camming effect whereby further rotation of the rock shaft tends to draw the lower edge of the hood both inwardly and downwardly. The shaft being flexible and being provided with relatively long spaces which are free from restricting bearings, a certain spring action or play is permitted which adds to the locking effect and at the same

time compensates for irregularities and prevents undue strain on any part of the device. It is necessary to make the edge B^3 of sufficient length to engage the crank arms B^1 throughout a reasonable range. This provides for irregularities in dimension and form of the various parts and also for irregularities in assembly of the parts. The member B^{12} serves as an upper stop to prevent any possible overriding of the crank arms B^1 over the inclined edge B^3 .

In some circumstances it may be desirable to employ additional means for limiting the outward movement of the lower edge of the hood. In such case we may provide the opposed members D and D^2 whereby, when the hood is in the position in which it is shown in Figure 4 it is held against outward movement and the main function of the latching means then is to draw the lower edge of the hood down and to prevent rattle or play.

The recurved form of crank arm shown in Figure 9 we find to be particularly advantageous owing to the fact that the bearings for the ends of the rock shaft may be generally aligned with the point of engagement of the crank arms and the abutment edges G^5 . The result is a particularly firm locking effect with a minimum of undesired play or spring, and a freedom from rattling.

We illustrate, as in Figures 2 and 3, means, namely the depression B^{10} for more or less locking the cam in latching position although this locking effect is insufficient to prevent ready manual movement of the handle C^1 .

We claim:

1. A latching device for an automobile hood which includes a plurality of latch abutments positioned within the hood and laterally inwardly spaced therefrom when the hood is in closed position, a rock shaft adapted to be supported upon the interior of said hood, said shaft having an intermediate offset portion, a cam member, adapted to engage said offset portion, rotatably mounted within and upon the hood, an exterior handle adapted to rotate said cam member, and portions adapted to engage said latch abutments, and means, associated with said cam member, adapted to prevent retrograde rotation of the rock shaft in response to pressure thereagainst, said means including a lateral extension of said cam adapted to overlie said offset portion when the device is in locking position, said lateral extension, and the portion of the offset opposed thereto, being in general parallelism with the rock shaft.

2. A latching device for an automobile hood which includes a plurality of latch abutments positioned within the hood, a rock shaft rotatably mounted upon the interior of the hood, and means for rotating it including an offset portion intermediate the ends of

the shaft, and a cam opposed to said offset portion and an exterior handle for rotating said cam, crank members associated with said rock shaft, adapted to engage the abutments in response to rotation of the rock shaft, said cam member being adapted to override said offset portion at the conclusion of the camming excursion, and to lock it in position against retrograde rotation. 70

3. A latching device for an automobile hood, adapted to draw the lower edge of a double hinged hood closure downwardly and inwardly into engagement with the opposed portions of the automobile, which includes a rock shaft mounted on the inner face of the closure for rotation about a generally horizontal axis, cranks associated with said rock shaft, cam members positioned within said closure for engagement with said cranks, said cranks being normally at all times in camming relationship with said cam members when the closure is locked, said cranks being adapted, in response to their engagement with the cam members, to draw the lower edge of the hood closure downwardly and inwardly against the opposed portions of the automobile, and means for rotating said cranks into camming locking engagement with the cam members, including an additional crank associated with the rock shaft, a handle exterior to the closure, a handle shaft pivoted to the closure and a cam associated with said handle shaft, within the hood closure, said cam being adapted to engage and rotate said last mentioned crank in response to rotation of the handle and the handle shaft. 75

4. A latching device for an automobile hood, adapted to draw the lower edge of a double hinged hood closure downwardly and inwardly into engagement with the opposed portions of the automobile, which includes a rock shaft mounted on the inner face of the closure for rotation about a generally horizontal axis, cranks associated with said rock shaft, cam members positioned within said closure for engagement with said cranks, said cranks being normally at all times in camming relationship with said cam members when the closure is locked, said cranks being adapted, in response to their engagement with the cam members, to draw the lower edge of the hood closure downwardly and inwardly against the opposed portions of the automobile, and means for rotating said cranks into camming locking engagement with the cam members, including an additional crank associated with the rock shaft, a handle exterior to the closure, a handle shaft pivoted to the closure and a cam associated with said handle shaft, within the hood closure, said cam being adapted to engage and rotate said last mentioned crank in response to rotation of the handle and the handle shaft, and means for prevent- 800

ing retrograde rotation of the rock shaft when in locking position.

5. A latching device for an automobile hood, adapted to draw the lower edge of a double hinged hood closure downwardly and inwardly into engagement with the opposed portions of the automobile, which includes a rock shaft mounted on the inner face of the closure for rotation about a generally horizontal axis, cranks associated with said rock shaft, cam members positioned within said closure for engagement with said cranks, said cranks being normally at all times in camming relationship with said cam members when the closure is locked, said cranks being adapted, in response to their engagement with the cam members, to draw the lower edge of the hood closure downwardly and inwardly against the opposed portions of the automobile, and means for rotating said cranks into camming locking engagement with the cam members, including an additional crank associated with the rock shaft, a handle exterior to the closure, a handle shaft pivoted to the closure and a cam associated with said handle shaft, within the hood closure, said cam being adapted to engage and rotate said last mentioned crank in response to rotation of the handle and the handle shaft, and means for preventing retrograde rotation of the rock shaft when in locking position, including a gripping connection between the cam and the crank, the cam being channelled to engage and grip the crank when the rock shaft is in locking position.
6. A latching device for an automobile hood, adapted to draw the lower edge of a double hinged hood closure downwardly and inwardly into engagement with the opposed portions of the automobile, which includes a rock shaft mounted on the inner face of the closure for rotation about a generally horizontal axis, cranks associated with said rock shaft, cam members positioned within said closure for engagement with said cranks, said cranks being normally at all times in camming relationship with said cam members when the closure is locked, said cranks being adapted, in response to their engagement with the cam members, to draw the lower edge of the hood closure downwardly and inwardly against the opposed portions of the automobile, and means for rotating said cranks into camming locking engagement with the cam members, including a handle member mounted exteriorly of the hood closure, a shaft therefor rotatably mounted upon the closure, a cam member associated with said shaft and positioned within the closure, the rock shaft being provided with an offset cam portion opposed to said cam member, the cam member being adapted to over-ride and engage the offset cam portion of the rock shaft when the rock shaft is rotated to the extreme

limit of its movement, and positively to lock it in such position.

Signed at Chicago, county of Cook and State of Illinois, this 7th day of May, 1929.

NORTON A. MEARS.
DIBRELL P. HYNES.
